BUCCAL TUBE FOR ORTHODONTIA

Archie E. Brusse, Denver, Colo., assignor to Rocky Mountain Metal Products Co., Denver, Colo., a corporation of Colorado

Application April 16, 1945, Serial No. 588,490

3 Claims. (Cl. 32—14)

1

This invention relates to an orthodontic appliance and more particularly to a buccal tube for use with an arch wire.

One of the objects of this invention is to produce an improved buccal tube that can be easily and economically manufactured and readily attached to a tooth band.

Another object is to produce an improved buccal tube which is so constructed that an arch wire can be efficiently attached to a tooth band.

A further object is to so construct a buccal tube that a tie wire can be conveniently associated therewith to firmly tie the arch wire to the tube.

A still further object is to produce a buccal tube from a single piece of flat stock so as to provide separate openings for receiving an arch wire and a tie wire.

A more specific object is to so produce a buccal tube from a single piece of flat stock that the arch wire receiving tube portion will be strengthened by an underlying part formed from the single piece of stock.

Other objects will become apparent from the following description taken in connection with the accompanying drawings in which:

Figure 1 is a top view of a buccal tube embodying my invention;

Figure 2 is a bottom view of the buccal tube of Figure 1;

Figure 3 is a sectional view taken on the line 3—3 of Figure 2;

Figures 4 and 5 are top and bottom views of a buccal tube showing a construction similar to Figures 1 to 3 but additionally embodying a tie wire anchor extension; and

Figure 6 is a section view taken on the line 6—6 of Figure 5.

Referring to the drawings in detail and first to Figures 1 to 3, inclusive, the buccal tube shown comprises a sheet 1 of relatively thin material such as, for example, stainless steel. The sheet is slightly more than twice as long as the final width of the buccal tube and the width is approximately half the length. At a place adjacent to one end of the sheet, but spaced therefrom, the material is deformed to provide an arched portion 2, thus providing on one side of the arched portion a short flange 3 and on the other side an extension generally indicated by the member 4. This extension is bent backward on itself to provide a short flange 5, substantially the same width as the flange 3 and an underlying portion 6 of such length as to completely underlie the flange 3 as well as the flange 5. This

2

underlying portion closes the open side of the arched portion 2 and thus provides with the arched portion a passage 7 open only at its ends. This underlying portion opposite the open end of the arched portion 2 is deformed to provide an arched portion 8, this second arched portion projecting in the same direction as the arched portion 2 but being arched to a lesser extent. The arched portion 8 thus provides a transverse depression 9 in the outer surface of the underlying portion 6 which is parallel with the passage 7. The completed buccal tube may be made from a single sheet or a number of buccal tubes made simultaneously in a long strip properly arched and bent and from which the single tubes are cut off.

The buccal tube, as thus constructed, is ready for orthodontic use and when so used is employed as a supporting bracket for an arch wire employed in correcting malposed teeth in the dental arch. This arch wire is indicated in the dotted lines and referred to by the number 10. The buccal tube as employed to support the arch wire is attached to a tooth band which encircles a tooth of the dental arch. In attaching this tube to the band the tube is placed against the exterior surface of the band with the outer surface of the underlying portion 6 of the tube engaging the band surface. The tube is then attached to the band surface by welding the underlying portion 6 to the band. This welding operation may be so performed that the flange 3 will be secured to the underlying portion 6 by the same weld that is employed to weld said portion to the tooth band 7. When the buccal tube is so positioned on the band there is provided the passage 7 and a second parallel passage formed by the depression 9 in the outer surface of the underlying portion 6. In order that the arch wire may be firmly held in the passage 7 of the buccal tube, an additional securing means is provided comprising a tie wire 11, shown in Figures 1, 2 and 3. This tie wire extends through the passage formed by the depression 9 and the ends thereof are looped around the arch wire, all as indicated in Figures 1 and 2. When the tie wire is in position the arch wire will then be firmly held in the buccal tube through which it extends.

The buccal tube, when constructed as shown in Figures 1 to 3 and then welded to a tooth band, insures that the arch wire will be efficiently attached to and supported by a tooth. The construction permits separate passages for receiving the arch wire and the tie wire and because of this the tie wire can operate very efficiently in form-

ing a firm connection between the arch wire and the tooth. The buccal tube is provided with ample flanges on each side of the arched portion whereby secure welding can be accomplished to attach the buccal tube to the tooth band yet the entire structure is of sufficiently small size as not to be overly uncomfortable with respect to the cheeks and other mouth parts on the exterior side of the dental arch which may come in contact with the tube.

In Figures 4, 5 and 6 the modified buccal tube is of a construction similar to that of Figures 1 to 3. There is provided, however, a lateral extending portion 12 which extends from the arched portion 2. In forming the arched portion 2, this extension 12 is also arched and in the final construction of the tube the portion 12 becomes a continuation of the arched portion, all as clearly shown in the figures. The purpose of this extension 12 is to provide an anchor means for the tie wire 14, which wire is looped about the extension after it has been passed through the depression 9 in the outer surface of the underlying portion 6 of the tube. Thus with the extension 12 there is provided an integral part on the tube to which the tie wire can be anchored and thereby firmly hold the arch wire 10 in the passage 7 of the tube and prevent any relative movement between the tube and the arch wire.

Being aware of the possibility of modifications in the structures shown and described, I do not intend that the invention embodied therein be in any way limited except in accordance with the appended claims.

What is claimed is:

1. An orthodontic bracket formed of a single

sheet of material and comprising upper and lower contiguous positions, said upper portion being bent to form an arch wire receiving tubular socket extending between two opposite edges thereof, and the lower portion having its outer surface depressed so as to provide a tie wire receiving passage when said lower portion is attached to a supporting surface with respect to which an arch wire is to be secured.

2. An orthodontic bracket formed of a single sheet of material and comprising upper and lower contiguous positions, said upper portion being bent to form an arch wire receiving tubular socket extending between two opposite edges thereof, and the lower portion having its outer surface depressed so as to provide a tie wire receiving passage coextensive with said tubular socket when said lower portion is attached to a supporting surface with respect to which an arch wire is to be secured.

3. An orthodontic bracket of the character described in claim 1 wherein the part of the upper portion which defines the tubular socket extends beyond one edge of the lower portion.

ARCHIE B. BRUSSE.
